UNITED STATES PATENT OFFICE.

OSCAR H. ANDERSON, OF GRAND HAVEN, MICHIGAN, ASSIGNOR TO STORY & CLARK PIANO CO., OF GRAND HAVEN, MICHIGAN, A CORPORATION OF ILLINOIS.

PNEUMATIC MOTOR.

Application filed February 12, 1923. Serial No. 618,533.

To all whom it may concern:

Be it known that I, OSCAR H. ANDERSON, a citizen of the United States, residing at Grand Haven, in the county of Ottawa and State of Michigan, have invented a new and useful Improvement in Pneumatic Motors, of which the following is a specification.

This invention relates to improvements in pneumatic motors. For the purpose of illustrating my invention I have shown a pneumatic motor of the type ordinarily used for operating musical instruments such as for example as player-pianos.

My improved motor can be easily and cheaply made and will be found to be efficient and quiet in operation. It is so constructed that there will be a minimum of wear on the different parts and also the desired flexibility. The motor is especially adapted for use in connection with mechanical musical instruments such as player pianos.

The features and advantages of my invention will appear in the following specification and drawings in which—

Fig. 1 is a view in front elevation of a pneumatic motor embodying the features of my invention. Fig. 2 is a view of the same in end elevation. Fig. 3 is a view taken as indicated by the line 3 of Fig. 1. Figs. 4, 5, and 6 are views similar to Fig. 3 showing the bellows in different positions. Fig. 7 is a view similar to Fig. 5, showing a modified form and Fig. 8 is a similar view showing another modified form of device.

As shown in the drawings, the motor comprises in general a plurality of double bellows here shown as three in number indicated by A B and C respectively. These bellows are provided in the ordinary manner with connecting rods 10, operating on the cranks 11 to drive the shaft 12. Slide valves of ordinary form, as indicated by 13 operated by the valve rods 14 are also provided. 15 indicates a manifold, and 16 and 17 are the ports leading to the upper and lower pneumatic respectively of each double bellows. My invention lies in the particular construction of the double bellows itself and will be described more in particular hereinafter.

Since each of the bellows is similar in construction I will describe in detail but one.

55 The double bellows A is shown in cross

section in Fig. 3. It will be noted that this double bellows comprises an upper pneumatic A' and a lower pneumatic A''. The upper pneumatic A' consists of a swinging member 20 and a fixed member 21 on a supporting block 80, the bellows material 22, and the material 23 attached to the lower ends of the swinging and fixed members 20 and 21 to form a hinge joint.

The lower pneumatic A'' consists of the swinging member 30 and fixed member 31, bellows material 32 and hinge 33 which are similarly arranged.

The two pneumatics are connected together by means of a board or strip 40 which is secured to the swinging member 20 by means of the screws 41. Since the pivot lines 23 and 33 of the upper and lower pneumatics respectively do not coincide, means must be provided for permitting play between the swinging member 30 of the lower pneumatic and the connecting member 40. Such means comprise a hook 42 at the lower end of the swinging member 30 which engages the lower end of the strip or connecting member 40. This hook is loose enough to permit separation of the members 40 and 30 and also sliding movement of each with respect to the other. The hook 42 is preferably made out of a piece of sheet metal and may be attached to the member 30 by means of the screw 44, the head of which I have here shown as being accommodated in a recess 45 in the under side of the connecting member 40, such recess being of sufficient size to permit the movements of the members 40 and 30 with respect to each other above mentioned.

The construction above described permitting play and movements between the members 40 and 30 permits the use of ordinary rubber cloth strip hinges on both the upper and lower pneumatics at 23 and 33 respectively. That is, each of the hinges 23 and 33 may be of the common form pivoting on straight lines, without any looseness or fullness.

The operation of the device may be better understood by reference to Figs. 4, 5 and 6 which show the bellows in three different positions. In Fig. 4 the lower pneumatic is fully expanded, and there appears the full separation between the members 40 and 30. In Fig. 5 the pneumatics are equally expanded with the result that the swinging

member 30 is somewhat closer to the connecting strip 40. In Fig. 6, the lower pneumatic is shown at the limit of its deflated position, and in this position the swinging member 30 is practically against the connecting strip 40.

In order to give ample room for the collapsing of the lower pneumatic A'', I have made the swinging member 20 slightly thicker than the swinging member 30. Such accommodation for the members 30 and 31, when the lower pneumatic A'' is fully compressed, may, however, be provided in other ways. For example, as shown in Fig. 7, the stationary member 31' (corresponding to the member 31 in the preferred form) may be slightly depressed, or set down a little lower or a little further into the supporting block or member 80. Such depression is provided by forming the depression 81' in block 80. Or if desired, as shown in Fig. 8, the member 31'' (corresponding to the member 31 in the preferred form) may be made a little thinner than the member 21.

While I have shown and described certain embodiments of my invention, it is to be understood that it is capable of many modifications. Changes therefore in the construction and arrangement may be made without departing from the spirit and scope of the invention as disclosed in the appended claims, in which it is my intention to claim all novelty inherent in my invention as broadly as possible in view of the prior art.

What I claim as new, and desire to secure by Letters Patent is:

1. A pneumatic motor having a double bellows comprising a pair of pneumatics with their hinged ends adjacent, each pneumatic having a fixed member and a swinging member, a connecting member rigidly attached to the swinging member of one pneumatic, and a loose connection between said connecting member and the swinging member of the other pneumatic.

2. A pneumatic motor having a double bellows comprising a pair of pneumatics with their hinged ends adjacent, each pneumatic having a fixed member and a swinging member, a connecting member rigidly attached to the swinging member of one pneumatic, and means for connecting said

connecting member to the swinging member of the other pneumatic, said means permitting the requisite movement between said members caused by the operation of the bellows.

3. A pneumatic motor having a double bellows comprising a pair of pneumatics with their hinged ends adjacent, each pneumatic having a fixed member and a swinging member, a connecting member rigidly attached to the swinging member of one pneumatic, and a loose connection between said connecting member and the swinging member of the other pneumatic, said connection comprising a hook attached to the end of the swinging member and engaging the end of the connecting member.

4. A pneumatic motor having a double bellows comprising a pair of pneumatics with their hinged ends adjacent, each pneumatic having a fixed member and a swinging member, a connecting member rigidly attached to the swinging member of one pneumatic, and a connection between said connecting member and the swinging member of the other pneumatic permitting separation of said members.

5. A pneumatic motor having a double bellows comprising a pair of pneumatics with their hinged ends adjacent, each pneumatic having a fixed member and a swinging member, a connecting member rigidly attached to the swinging member of one pneumatic, and a connection between said connecting member and the swinging member of the other pneumatic permitting sliding of said members with respect to each other.

6. A pneumatic motor having a double bellows comprising a pair of pneumatics with their hinged ends adjacent, each pneumatic having a fixed member and a swinging member, a connecting member rigidly attached to the swinging member of one pneumatic, and a connection between said connecting member and the swinging member of the other pneumatic permitting separation of said members and sliding of the same with respect to each other.

In witness whereof, I have hereunto set my hand this 7th day of February A. D. 1923.

OSCAR H. ANDERSON.
